CHART TABLE

Eppa L. Dodson, Washington, D. C.

Application August 3, 1945, Serial No. 608,768

4 Claims. (Cl. 40—86)

1

My invention relates to an improvement in a chart table.

For many years mariners have of necessity carefully followed coast and geodetic charts to aid them in navigation. These charts are printed on large sheets of special paper, and all markings thereon are carefully arranged according to a predetermined scale.

In using these charts, a mariner preferably lays a chart out on a flat surface so that he may readily use his instruments, such as parallel rules, protractors, dividers and the like, while plotting a course he intends to navigate. Often a given course to be followed will require the use of more than one chart, and consequently one chart must be removed and replaced with another.

To obviate some of the common objections found with some chart tables in present day use, I have developed my chart table.

An object of my invention is to provide a chart table having rollers on which a plurality of charts, which have been secured together along opposite margins, may be readily rolled and moved over a flat surface.

A further object is to provide a chart table over which a series of charts may be passed and be held securely and flatly for use.

A further object is to provide a chart table which is adapted to hold a series of prearranged charts on a flat surface, and which may be placed on any convenient surface such as a desk, table or the like, or which may be hung on a bulk-head, wall or the like.

A further object is to provide a chart table over which a series of charts which have been secured together may be advanced or retracted from position over a flat surface.

A still further object is to provide a chart table over which a series of charts may be held flat against a surface for inspection and use.

In the drawings,

Fig. 1 is a broken away view in front elevation,
Fig. 2 is a top plan view,

Fig. 3 is a broken away view in side elevation,

Fig. 4 is a broken away view in side elevation showing the chart table in position for use.

Fig. 5 is an enlarged fragmentary horizontal cross-section on the line 5—5 of Fig. 1, looking in the direction of the arrows,

Fig. 6 is an enlarged fragmentary horizontal cross-section on the line 6—6 of Fig. 1 looking in the direction of the arrows,

Fig. 7 is an enlarged fragmentary vertical cross-section on the line 7—7 of Fig. 3, looking in the direction of the arrows, and

2

Fig. 8 is an enlarged fragmentary detail, in side elevation, of a roll holder.

I utilize a substantially large rectangular piece of plywood, "Masonite," or the like material 2, which is preferably secured in position in a rectangular frame 4 of suitable material such as wood, metal, plastic or the like. The surface of the plywood 2 is positioned within the frame 4 so that their external surfaces will be in one plane.

10 On the under side of the plywood 2 space is provided for the supporting legs 6 which are hingedly secured to one side member of the frame 4 so that, when not in use, the leg 6 may be hinged into the position in which it is shown in the figures (except Fig. 4). When the leg 6 is held in this position, it is frictionally held by a spring-pressed ball bearing 8, of conventional design. In Fig. 4, the leg 6 is shown in a position to hold the chart table at a slant relative to the bulk-head 10 to which it is hingedly secured by means of the ear 12 which is provided with a hole for the insertion of a nail, screw, hook or lug positioned in the bulk-head 10.

With the chart table thus constructed, I attach to opposite corners thereof outstanding plates 16, preferably of relatively thin sheet metal, and which plates are provided with a substantially wide slot cut approximately in the longitudinal center thereof.

30 In the slots above referred to in the plates 16, I provide a slide 18, which also is preferably of metal. The slide 18 is provided with grooves in opposite sides and into which the edges of the plate 16 are adapted to fit so that the slide 18 may be adjusted relative to the plate 16 by sliding up and down in the slot provided in the plate.

The slide 18 is drilled in the approximate center thereof for a relatively short shaft 20 to pass therethrough. The shaft, on one end thereof has a crank 22 attached, and on the other end has secured thereto a circular plate 24. The circular plate 24 is provided with two studs 26 outstanding from the plate on the side thereof remote from the shaft 20. These studs 26 are adapted to be inserted in holes provided for the same in a circular plate 27 attached to one end of the roller 28, which is provided for the charts to be wound upon. The slide 18 is spring-urged toward the chart table by the tension spring 30 which is attached at one end thereof to the slide 18 and at the other end to the plate 16.

At the other end of the roller (and the opposite side of the chart table) I provide a similar construction but the short shaft passing through

the plate 18 on this side extends therethrough to provide a pivot point for the end of the roller. With this construction it will be understood that the roller 28 will be held by the shaft 20 extending through the plates 18, and will be spring-urged toward the chart table.

The roller 28 is provided with a radial slot 29 extending approximately throughout its length. The slot 29 is relatively narrow, such as a saw-kerf and is preferably from about half to three-quarters of an inch deep. This slot is provided so that an edge of a chart may be inserted therein for the purpose of holding the chart on the roller 28 for the purpose of being wound therearound.

Secured to the chart table, and extending slightly above the surface thereof, I provide small rollers 32. These rollers 32 are positioned directly beneath the rollers 28 and in axial alignment therewith. These rollers 32 are provided so that the chart wound around the rollers 28 will be held between the rollers 28 and 32, and will be spaced slightly apart from the surface of the plywood 2 of the chart table.

By the use of my chart table it will be seen that several charts may be secured together and wound upon a pair of rollers 28 which may be readily inserted in their proper positions on my chart table, presenting the desired chart for inspection, measurement and course drafting, by merely rolling and unrolling, respectively, from one roller or the other. In this manner charts may be conveniently handled and changed when desired. Also the desired chart will be held in a flat position on the chart table so that desired, and necessary, mariners' instruments can be conveniently and accurately used. Also the chart table may be conveniently moved from one place of use to another.

While it is obvious that I have designed my chart table primarily for use in connection with the normal and official coast and geodetic charts, yet it will be readily understood that it may be utilized in connection with the use of charts or maps produced for and used by aeronautical navigators. Obviously also, road maps for automobile tourists may be utilized on my chart table, and in this latter case it may be found convenient to make the table relatively small so that it may be conveniently carried in an automobile for such use.

I claim:

1. A chart table including a flat rectangular surface, outstanding plates secured on opposite

edges near the corners of said rectangular surface, slides engaging the said outstanding plates, rollers interposed between said outstanding plates, axles passing through the said slides and engaging the ends of the said rollers, and tension springs drawing the slides and rollers toward the said flat rectangular surface.

2. A chart table including a flat rectangular surface, outstanding plates secured on opposite edges near the corners of said rectangular surface, slides engaging the said outstanding plates, rollers interposed between said outstanding plates, axles passing through the said slides and engaging the ends of the said rollers, and tension springs drawing the slides and rollers toward the said flat rectangular surface, secondary rollers outstanding from the rectangular surface and positioned to be axially parallel with the axes of the said first mentioned rollers, the said secondary rollers bearing against the said first-mentioned rollers.

3. In a chart table a flat rectangular surface, plates outstanding from said surface near the corners thereof, slides mounted in grooves in said plates, axles passing through said slides, rollers interposed between oppositely positioned axles, secondary rollers mounted on the said flat surface and axially parallel with the axes of the said first mentioned rollers, and a strip of flexible material adapted to be wound on the said first mentioned rollers and to pass between those said rollers and the said secondary rollers.

4. In a chart table a flat rectangular surface, plates outstanding from the said rectangular surface near the corners thereof, slides mounted in grooves in the said plates, stub axles extending through the said plates and adapted to engage a roller positioned between the said plates, secondary rollers extending above the said flat surface, and axially parallel with the axes of the said first mentioned rollers, and springs urging the said rollers into engagement with the said secondary rollers.

EPPA L. DODSON.
